[57] CLAIM

The ornamental design for a bicycle kickstand support, as shown and described.

DESCRIPTION

FIG. 1 is an environmental perspective view of the bicycle kickstand support showing my new design with a bicycle kickstand shown in broken lines but forming no part of my design;

FIG. 2 is a front elevational view thereof;

FIG. 3 is a rear elevational view thereof;

FIG. 4 is a left side view thereof;

FIG. 5 is a right side view thereof;

FIG. 6 is a bottom view thereof; and,

FIG. 7 is a top view thereof.
